UNITED STATES PATENT OFFICE.

HENRY RICHARDSON, OF PASSAIC, NEW JERSEY, ASSIGNOR TO RICHARDSON SCALE COMPANY, OF PASSAIC, NEW JERSEY, A CORPORATION OF NEW JERSEY.

CAR-DOOR OPENER.

Application filed May 22, 1922. Serial No. 562,916.

The present invention relates to improvements in apparatus adapted for use in the unloading of railroad cars loaded with material in bulk, and more especially cars of the box-car type loaded in the customary way with grain.

The primary object of the invention is to provide a simplified, improved and inexpensive device for pushing in and thus opening the door of the car to enable the grain or contents thereof to flow or to be otherwise discharged therefrom. The present invention provides a device of this character which can be easily and quickly brought into position opposite to the door to be opened, the device being so constructed and operative that a relative movement between the car and the door-pushing device, in a direction longitudinally of the car, will force 10 loose and effectively push in the door without the necessity of destroying the door and without injury to the car. A door-pushing device of this character enables cars to be unloaded quickly and inexpensively, especially in those instances where an elaborate and expensive car-loading installation is not available or the cost of such an installation would be prohibitive.

To these and other ends the invention consists in certain improvements and combinations and arrangements of parts, all as will be hereinafter more fully described, the features of novelty being pointed out particularly in the claims at the end of the specification.

In the accompanying drawings:—

Figure 1 is a diagrammatic view illustrating, by the full lines, the manner in which a door-pushing device constructed in accordance with the present invention is positioned opposite to the car door to be opened, and indicating by the dotted lines the manner in which the door is opened.

Figure 2 is a diagrammatic view showing the manner in which the opening of the car door is initiated.

Figure 3 is a side elevation of a door-opening device constructed in accordance with the preferred embodiment of the invention.

Figure 4 illustrates the door-opening device in end elevation showing the same positioned to open the door of a grain car.

Figure 5 is a view similar to Figure 4 but showing the door opening device in the

retracted position which it occupies prior or subsequent to its operation, thus permitting transit of the car or cars past the door-opening device without obstruction.

Figure 6 is a perspective view of a door-opening device constructed in accordance with another embodiment of the invention.

Figure 7 is a perspective view of another embodiment of the invention wherein, means is provided for adjusting the length of the door pusher to accommodate it to cars of different widths.

Similar parts are designated by the same reference characters in the several views.

Door-opening devices embodying the present invention are adapted for use generally in all instances where it is desirable or necessary to push in and thus open the door of a car preparatory to or as a part of the operation of unloading the contents thereof, although it is particularly useful in situations where an elaborate car-unloading installation embodying means for tilting the car is not available or the cost of such an installation would be prohibitive. The preferred embodiments of the invention are shown in the accompanying drawings and will be hereinafter described in detail, but it is to be understood that the invention is not restricted to the precise construction shown as equivalent constructions are contemplated and these will be included within the scope of the claims.

In the present instance, A represents a railroad car of the box-car type ordinarily used in the carrying of grain in bulk, it being customary to nail or otherwise secure boards B against the inner sides of the upright beams or jambs C at the opposite sides of the door opening, these boards extending up to a suitable height above the floor E of the car, so that the grain in bulk designated F may be loaded in the car to the desired depth.

The door-opening device is suitably mounted at one side of the track on which the car to be unloaded may rest and preferably the door-opening device is so mounted that it may travel or be shifted in a direction longitudinally alongside of the car rails. In Figures 1 to 5, inclusive, the door-opening device comprises a carriage 1 which is suspended or otherwise mounted to travel along an overhead rail 2 which is suitably supported alongside of and in

parallelism with the car rails, the carriage being provided with rollers 3 adapted to travel along the lower flange of the rail 2 which, in the present instance, is shown as 5 consisting of an I-beam and the lower end of the carriage is guided and sustained from lateral swing or displacement by a lower guide or rail 4 which may be placed directly beneath and in parallelism with the rail 10 2, the lower end of the carriage being provided, in the present instance, with a beam or member 5 which is confined laterally but travels longitudinally in a channel formed in the top of the lower rail 4. 15 Means is provided in the present instance for locking or securely holding the carriage of the door-opening device from movement longitudinally of the rails 2 and 4 after the door-pushing device has been brought into a 20 position to operate on the car door. As shown, a pair of locking bolts 6 are guided to move vertically in the lower ends of upright members 7 which are secured to or form a part of the carriage, these bolts being adapted when lowered to engage in holes 25 8 in the lower rail 4, thus securely holding the carriage from shifting longitudinally on the rails, but when the bolts are elevated or retracted, the carriage may be shifted longitudinally of the rails to move it to or from 30 operative relation with the car door or the car door opening. The uprights 7 may advantageously be constructed of tubular form as shown to accommodate the bolts 6 and 35 guide them and the bolts may be attached to rods or cables 9 which extend upwardly through the tubular uprights and are connected to bell-crank levers 10 pivoted at 40 11 on the upper portion of the carriage and toggle links 12 may be operatively connected to the lower arms of the bell-crank levers and the middle pivot 13 of these toggle links may have a suitable handle 14 attached thereto. By this construction, when the handle 45 14 is in its lower position, as shown in Figure 3, the toggle links 12 will be in alignment, or substantially so, and the locking bolts 6 will be elevated or retracted, the carriage being then unlocked so it may 50 be shifted along its rails; but when the handle 14 is pushed upwardly the toggle links 12 will be bent or flexed and the bolts 6 will thus be lowered, so that they engage in the locking holes 8 in the lower rail, the carriage being thereby locked securely from movement or displacement along its 55 rails.

The door-opening device proper 60 comprises pairs of bars or props 15 and 16, the upper and lower arms 15 being operatively connected to fittings 17 which are supported or sustained by one of the uprights 7, the other ends of these arms being connected to a frame or pusher 18 and the other arms 16 are similarly connected to fittings 19

mounted on the other upright 7 and connected to a frame or pusher 20. The fittings 17 and 19 are pivotally mounted on the respective uprights 7, so that the pairs of bars or props 15 and 16 may be swung 70 in unison or substantially so about these uprights as axes and the free ends of the bars or props are so connected that they will swing in definite relation to one another about the uprights 7 as axes. As shown in 75 the present instance, a connection is provided between the frames or pushers 18 and 20 which comprises a pair of members 21 and 22, these members being pivotally connected at 23 and 24 to the respective frames 80 and relatively adjustable longitudinally to vary the spacing between the frames 18 and 20. As shown, the members 21 and 22 have a telescopic relation and a pin 25 serves to lock them in the desired relation. 85

In order to enable the door-opening or pushing device to be retracted with respect to the car rails and thus permit movement of cars past the door opening without obstruction, the bars or props 15 are pivotally connected at 26 and 27 to the fittings 17 and the frame 18, respectively, and the bars or props 16 are similarly connected by the pivots 28 and 29 to the fittings 19 and frame 20, respectively, the bars and frames thus providing a structure which can be lowered to bring the bars into substantially horizontal position with the lower ends of the frames resting on the car floor which forms the sill of the car opening, as shown in 90 Figure 4, or the arms may be swung upwardly more or less to elevate the frames 18 and 20 and as the arms 15 and 16 swing about the pivots 26 and 28 of the fittings 17 and 19, the effect of this movement will be to retract the door-pushing frames 18 and 20 in a direction laterally of the car rails or a car standing thereon, substantially 95 as shown in Figure 5.

The weight of the bars 15 and 16, the frames 18 and 20 and the connection between the frames is preferably counter-balanced in order to facilitate manipulation of the door pusher. As shown in the present instance, cables 30 are attached to the respective frames 18 and 20, these cables passing upwardly over idler pulleys 31 on the top of the carriage 1 and the ends of these cables extend downwardly and have suitable counter-weights 32 attached thereto, the counter-weights being advantageously guided to work vertically between the uprights 9 of the carriage and the adjacent upright members 33 of the carriage. 110

The portions of the frames 18 and 20 which act on the car door to effect opening thereof are preferably provided with rollers 125 34 and 35 which may extend substantially throughout the height of these frames, these rollers being capable of acting effectively on 130

the boards or planks which constitute the door, but they will avoid damage or injury to the car door jamb or any other part of the car which they may engage during the 5 operation of opening the door.

The preferred mode of using a car door opener constructed as above described is as follows: The car to be unloaded is shifted along its rails to bring it opposite to the door 10 opening device which is arranged alongside of such rails or the door-opening device may be shifted along its rails to bring it into operative relation with the car door to be opened. While this is being done the frames 15 18 and 20 are preferably arranged in their elevated or retracted position, substantially as shown in Figure 5. After the door-opening device has been positioned opposite to the door to be opened, the frames 18 and 20 20 are swung downwardly until the lower ends of these frames rest on the sill or floor of the car at the bottom of the car door opening. It will be understood that the bars or props 25 15 are of such length relatively to the transverse distance between the car rails and the rails which support the car door opener that when the frames 18 are lowered to operative position, substantially as is shown in Figure 4, one of the frames, as the frame 30 18 or the roller 34 thereon, will come against the outer side of the door B which is to be opened, and this roller 34 will also abut against the adjacent door jamb and the bars 35 15 and 16 will occupy an inclined or oblique position relatively to the length of the car 40 rails or the rails on which the door opener is mounted. The connecting members 21 and 22 between the frames 18 and 20 are also preferably so adjusted that the rollers 45 34 and 35 will be spaced from one another a distance somewhat less than the spacing of the uprights 9 which constitute the axes about which the bars 15 and 16 are mounted to swing horizontally, so that when one of the rollers, as, for example, the roller 34, 50 engages its end of the door and rests against the adjacent door jamb, as is shown in Figure 1, the other roller as 35 will stand away from its respective end of the door for a suitable distance, as, for example, as shown in Figure 1. With the door pushers arranged in this way a relative longitudinal movement is caused to take place between the car and the door opener to cause the 55 door opening operation to be performed. Where this relative movement is accomplished by shifting the car along its rails, the carriage of the door opener is locked in relatively fixed position to its rails by lowering the bolts 6 and the car is shifted toward the left in Figure 1, in consequence of which the arms 15 and 16 will be swung about the uprights 9 as vertical axes toward a position perpendicular to the car rails or the rails on which the car opener is mounted. 60

The initial part of this relative shifting movement between the car and the car door opener causes the roller 34 which is in an advanced position relatively to the roller 35 to initiate the door opening operation by pushing in its respective end of the door B substantially as is represented in Figure 2, the roller 34 during this operation being sustained in working position by abutting against the adjacent door jamb C, and as 65 the relative longitudinal displacement between the car and the door opener proceeds and the bars or props 15 and 16 approach positions perpendicular to the lengths of the car rails or the door pusher supporting rails, the other roller 35 will come against its end of the door and both rollers 34 and 35 will then act substantially in unison to push the door B inwardly at both ends, the door being thus forced loose from its fastenings against the door jambs C and pushed into the car against the pressure of the grain therein. As the weight of the grain at the bottom of the door is greater than that at the top thereof, the door may have a tendency to drift upwardly as it is pushed in and the door will be free to move upwardly, as well as inwardly, due to the pivotal connections of the bars 15 and 16 which permit upward movement of the frames 18 and 20. The dotted lines in Figure 1 show the door B in its opened position, openings being provided between the ends of the door and the door jambs C and also beneath the door, through which openings the grain may freely flow and thus discharge from the car. After a sufficient quantity of the grain has discharged from the car, the door opener may be swung into its retracted position, substantially as shown in Figure 5, the boards constituting the door which has been opened may be removed, and the completion of the discharging of the contents of the car may be accomplished without obstruction by the door opener. After the door of one car has been opened the door opener may be unlocked from its rails and shifted longitudinally thereon to bring it into position to open the door of another car; or each car after its door has been opened and its contents discharged may be removed from a position opposite to the door opener and another car to be unloaded may be brought into operative relation with the door opener. 105 110 115 120 125 130

Figure 6 illustrates a door opener constructed in accordance with another embodiment of the invention. In this instance, the carriage 1^a is mounted on rails 4^a which extend alongside of and in parallelism with the rails for the cars to be unloaded, locking apertures 8^a being provided in a plate 8^b which may be fixed in place between the rails 4^a and arranged to cooperate with vertically movable locking bolts 6^a. These lock- 135

ing bolts may be mounted or guided in the lower ends of a pair of hollow standards 7^a which are mounted rigidly on the carriage 1^a and are provided with fittings 17^a and 19^a which are rotatable horizontally about these standards as axes. These fittings have the pairs of arms 15^a and 16^a pivoted thereto on the pivotal centers 26^a and 28^a and the outer ends of these arms are pivotally connected by the pivots 27^a and 29^a to frames 18^a and 20^a, the latter being provided with rollers 34^a and 35^a. The frames are adjustably connected by telescopically related members 21^a and 22^a which determine the spacing between the frames or their rollers. Cables 30^a are connected to the frames, they passing upwardly over pulleys 31^a on the tops of the standards 7^a and the cables are attached to counter-weights 32^a which counter-balance the weight of the frames and their connected bars or arms. The door opener shown in this instance may be used in the same way as that described in connection with the construction shown in Figures 1 to 5, inclusive, to accomplish the pushing in and opening of the car doors.

Figure 7 shows another embodiment of the invention wherein a single pair of arms is used and means is provided for adjusting the length of these arms to accommodate the door pusher to cars of different widths. In this instance the door pusher comprises a pair of arms 36 and 37 each composed of telescopic sections 38 and 39 and connected by a screw 40 revolvable in the section 38 and engaging the section 39 so that rotation of the screw in the appropriate direction will either lengthen or shorten the arm. The sections 38 of the respective arms are pivotally connected at 41 and 42 to an upright 43, so that the arms may swing vertically, and the upright 43 is pivoted by vertical pivots 44 to brackets 45 which may be secured to or form part of a carriage similar to the carriage 1 or 1^a, so that the arms may swing horizontally about the pivots 44 and may also be brought by the carriage into operative position relatively to the door of a car. The screws 40 which adjust the length of the arms may be conveniently operated by fitting worm wheels 46 on the screws and providing worms 47 to cooperate with the worm wheels, the worms being actuated by hand cranks 48 or other suitable means. The outer or free ends of the arms are connected by the pivots 49 to a frame or bar 50 which is adapted to engage the outer side of the door to be opened and abut against the adjacent door jamb, and while the arms of the door pusher extend in a direction oblique to the side of the car or the length of the rails which support it, and while the door pusher occupies this position, relative movement between the car and door pusher carriage or other support, in a direction longitudinally of the car will cause the

door pusher to swing from a position oblique to the length of the car toward a position perpendicular thereto, in consequence of which the door will be pushed in and thus opened in substantially the same manner as described in connection with Figures 1 to 6, inclusive. In this instance, the door pusher can be retracted or lifted out of the path of the car to allow the car and door pusher to be relatively shifted to bring the door pusher and door to and from operative relation.

It will be understood that while the door-opening operation has been described as performed by the longitudinal movement of the car relatively to the door opener, yet the door opening operation is effected by producing a relative longitudinal movement between the car and the door opener while the latter is operatively positioned with respect to the door to be opened and that this relative longitudinal movement may be produced in different ways, for example, the door opener itself may be shifted or moved by any suitable means longitudinally along its rails in the appropriate direction while the door opener is operatively positioned relatively to the door, the door opening operation, however, taking place in the same manner as has been hereinbefore described.

I claim as my invention:

1. A door opener for railroad cars comprising a pair of door pushers having means for mounting them to swing about substantially parallel vertical axes, the free ends of the pushers being adapted to engage a door in the side of a car, and means for holding the pair of door-pushers in relatively convergent relation whereby the door-engaging portions of the pushers will be brought into operation, one in advance of the other, to push in different portions of the door when the door pushers swing concurrently about their respective axes.

2. A door opener for railroad cars comprising a pair of door pushers mounted to swing about substantially vertical axes, the free ends of the pushers being adapted to engage a door in the side of a car, and a spacing member pivotally connecting the pushers toward their free ends, said member being adjustable to vary the distance between the free ends of the pushers.

3. A door opener for railroad cars comprising a door pusher having means for supporting it to swing both vertically and horizontally with respect to a side of a car, said pusher being movable by the vertically swinging motion into operative position at the outer side of a door in the side of the car and movable by the horizontal swinging motion from a position oblique to the length of the car toward a position perpendicular thereto in consequence of relative longitudinal movement between the car and the sup-

porting means for the door pusher, and means counter-balancing the door pusher in its vertical swinging motion.

4. A door opener for railroad cars comprising a pair of horizontally spaced upright pivots, and a pair of door pushers connected to swing in unison about said pivots, the free ends of the pushers being adapted to occupy longitudinally spaced positions at the outer side and toward the respective ends of a door in the adjacent side of the car while the pushers extend obliquely relatively to the length of the car, and the door pushers swinging about said pivots toward positions perpendicular to the length of the car in consequence of relative longitudinal movement between the car and said pivots, and a member connecting the door pushers to cause them to swing in substantial unison about their respective upright pivots.

5. A door opener for railroad cars comprising a pair of upright pivots, a pair of door pushers mounted to swing respectively about said pivots as axes and having their free ends adapted to engage the outer side of a door in the side of a car, and means connecting the door pushers to cause them to swing in unison about their respective pivots from positions oblique to the length of the car toward a position perpendicular thereto, said connecting means spacing the outer door engaging ends of the door pushers at a different distance than the spacing of said pivots.

6. A door opener for railroad cars comprising a pair of upright pivots having means for supporting them in spaced relation longitudinally at one side of a car, a pair of door pushers mounted to swing respectively about said pivots as axes and having their free ends adapted to engage the outer side of a door in the side of the car when the door pushers extend in a direction oblique to the length of the car, and a connection between the door pushers whereby one of the door pushers engages the door prior to the engagement of the other door pusher therewith and the door pushers are caused to swing in unison about their respective pivots in consequence of relative longitudinal movement between the car and said pivots.

7. A device for pushing in the door in the side of a railroad car comprising a pair of upright pivots adapted to be positioned opposite to such door, a pair of door pushers connected to swing horizontally about said pivots respectively, and a connection between the door pushers for spacing their free door engaging ends a distance less than the spacing of said pivots, thereby causing

the door engaging end of one pusher to engage the door in advance of the engagement of the other pusher therewith when the door pushers are arranged in positions oblique to the length of the car, relative movement between the car and the pivots in a direction longitudinally of the car causing the door pushers to swing from said oblique position toward a position perpendicular to the length of the car.

8. A device for pushing in the door in the side of a railroad car comprising a prop-like member having means for mounting it alongside a car to swing into a position oblique to the length of the car and thus engage the outer side of the door toward one end thereof and to abut against the adjacent door jamb, and a second prop-like member associated with the member first-mentioned and connected to the latter to swing in unison therewith and to hold said second-mentioned member in position to engage the door, relative longitudinal movement between the car and the mountings of said members causing the members to swing from said oblique position toward a position perpendicular to the length of the car and to cause said members to act successively and then concurrently to push in the door.

9. A device for pushing in a door in a side of a car comprising a pair of spaced upright pivots, a pair of door pushers each comprising a door-engaging member and a pair of bars pivoted for vertical swinging movement to the door engaging member and pivoted at their opposite ends for horizontal swinging movement about the respective upright pivot and also for vertical swinging movement relatively thereto, and a connection between the free ends of the door pushers for causing them to swing in unison about the respective upright pivots.

10. A door opener for railroad cars comprising a door pusher embodying longitudinally adjustable telescopic members, means pivotally connected to one of said members for supporting the door pusher alongside of a car to swing from a position oblique to the length of the car toward a position perpendicular thereto in consequence of relative longitudinal movement between the car and the supporting means, a screw carried by one of said members and engaging the other member, said screw being operative, when rotated, to relatively adjust said members longitudinally, and operating means for the screw on the member which carries the screw.

In testimony whereof I have hereunto set my hand.

HENRY RICHARDSON.
